UNITED STATES PATENT OFFICE.

JOHN F. O'CONNOR, OF CHICAGO, ILLINOIS, ASSIGNOR TO WILLIAM H. MINER, OF CHAZY, NEW YORK.

UNIVERSALLY-ADJUSTABLE ROLLER SIDE BEARING.

1,290,314.

Specification of Letters Patent.

Patented Jan. 7, 1919.

Application filed June 9, 1917. Serial No. 173,851.

To all whom it may concern:

Be it known that I, JOHN F. O'CONNOR, a citizen of the United States, residing at Chicago, in the county of Cook and State 5 of Illinois, have invented a certain new and useful Improvement in Universally-Adjustable Roller Side Bearings, of which the following is a full, clear, concise, and exact description, reference being had to the accompanying drawings, forming a part of 10 this specification.

This invention relates to improvements in universally adjustable roller side bearings.

The object of the invention is to provide 15 an anti-friction side bearing more particularly adapted for use on railway cars and wherein the anti-friction roller is rotatable about a horizontal axis and also pivotally mounted with respect to two other axes perpendicular to each other and to the axis of 20 rotation.

In the drawing forming a part of this specification, Figure 1 is a vertical sectional view, taken centrally of the improved side bearing and illustrating portions of the body and truck bolsters of a car in section. Fig. 2 is a horizontal sectional view, taken substantially on the line 2—2 of Fig. 1.

In said drawing, 10 denotes the under 25 portion of a body bolster and 11 the upper opposed portion of a truck bolster of a car.

The improved side bearing, designated generally by the reference A, comprises a base casting 12 riveted or otherwise suitably 30 secured to the truck bolster, said base casting having a pair of triangular shaped up-standing side walls 13—13. The inner faces of the side walls 13—13 at the top thereof, are vertically recessed, as indicated at 14—14, 35 to receive the reduced ends 15—15 of a non-rotatable axle 16. The improved anti-friction roller, as shown, comprises an outer element 17, an intermediate element 18, and an inner element 19. The inner element 19 comprises two halves 19^a and 19^b securely riveted together as by rivets 20, said halves 19^a and 19^b being provided with opposed semi-cylindrical recesses 21 which, when the 40 halves are riveted together, are adapted to 45 form bearings for a pair of diametrically disposed inwardly extending trunnions 22—22 formed on the inner side of the intermediate element 18. With this arrangement, it is apparent that the intermediate

element is oscillatable with respect to the 55 inner element 19 about an axis perpendicular to the axis of rotation of the inner element 19.

The intermediate roller element 18, which is preferably in the form of a casting, is provided on its exterior with a pair of outwardly extending trunnions 23—23 which are diametrically disposed and offset 90° from the inwardly extending trunnions 22. The trunnions 23 are seated in suitable bearings 24—24 formed in the two halves 17^a and 17^b of the outer roller element, said halves 17^a and 17^b being secured rigidly together as by rivets 25 in a manner similar to that employed in holding the two halves 70 of the inner element 19 together. With the arrangement just described, it is obvious that the outer element 17 is oscillatable with respect to the intermediate element 18 about an axis which is not only perpendicular to the 75 axis of rotation of the inner element 19 but also perpendicular to the axis of the trunnions 22. As will be understood, there is sufficient clearance between the outer and intermediate elements of the roller and between the intermediate and the inner elements, to permit the oscillation or adjustment hereinbefore referred to.

With the arrangement above described, it is obvious that the outer bearing portion of 85 the anti-friction roller which engages the body bolster is rotatable in the usual manner and in addition is permitted a universal adjustment about a pair of axes which are perpendicular to each other and also perpendicular to the axis of rotation of the roller 90 as a whole so that the anti-friction roller is adapted to accommodate itself to all conditions of service on a car.

I claim:

1. In a side bearing, the combination with a retaining member, of an anti-friction roller supported by said retaining member, said anti-friction roller comprising three 100 elements, all of said elements being relatively adjustable under load to thereby provide universal adjustability.

2. In an anti-friction bearing, the combination with a retaining member, of an axle carried by said member, an inner roller element rotatable on said axle, and concentric intermediate and outer roller elements mounted on the first named element, said 105

intermediate and outer elements being pivotally mounted with respect to said inner element.

3. As an article of manufacture, an anti-friction roller, said roller comprising an inner element, an intermediate element pivotally connected to the inner element, and an outer element pivotally connected to said intermediate element.
- 10 4. In a side bearing, the combination with a base casting having a fixed axle therein, of an anti-friction roller mounted on said axle, said anti-friction roller comprising three concentric elements all movable with respect to each other.

5. In an anti-friction bearing, the combination with a retaining casting, of an anti-friction roller rotatably mounted on said casting, said anti-friction roller comprising an intermediate element having a pair of inwardly extending lugs and a pair of outwardly extending lugs offset 90° from each other, an outer element pivotally supported by the outwardly extending lugs, and an inner element pivotally mounted on the inwardly extending lugs. 20 25

In witness that I claim the foregoing I have hereunto subscribed my name this 24th day of May, 1917.

JOHN F. O'CONNOR.
